OIL BURNER

Stanley Perry, Chicago, Ill.

Application March 10, 1950, Serial No. 148,890

12 Claims. (Cl. 158—28)

1

My invention relates to an improvement in liquid fuel burners and in controls therefor.

One purpose is to provide a control adapted to meter fuels of various densities at approximately constant flow rate selected by manual adjustment.

Another purpose is to provide automatic means for varying the metering orifice to permit accurate metering of fuels of various densities.

Another purpose is to provide automatic correction for changes in fuel density resulting from temperature variations.

Another purpose is to provide a gradual increase in the rate of fuel feed when the burner is starting.

Another purpose is to provide a gradual decrease in the fuel feed or supply rate before shutting off combustion air supply.

Another purpose is to provide a heat motor which controls the increase and decrease of fuel supply, as above pointed out, and also provides for normal operation.

Another purpose is to provide control means effective to feed fuel only when combustion air is available, and to control the rate of fuel flow in proportion to the amount of combustion air supplied.

Another purpose is to provide automatic termination of fuel supply effective when the supply of combustion air is interrupted.

Another purpose is to provide a switch mechanism for high-low operation of the burner when quick response to the thermostat is required.

Another purpose is to provide complete stoppage of the burner when no heat is required.

Other purposes will appear from time to time in the course of the specification and claims.

The invention is illustrated more or less diagrammatically in the accompanying drawings, wherein:

Fig. 1 is a vertical section with parts in elevation; and

Fig. 2 is a wiring diagram.

Like parts are indicated by like symbols throughout the specification and drawings.

Referring to the drawings, A generally indicates a burner assembly and B a float valve assembly. The float valve assembly is shown as including the housing or casing 1 with a preferably removable lid or cover 2. 3 is a liquid fuel supply line extending to any suitable source of liquid fuel not herein shown. 4 is a duct extending upwardly from the bottom of the housing 1 and having an interior bore in communication with the fuel line 3. In the position of the parts

2

as shown in Fig. 1, the open top of the bore is closed by a valve member 5 loosely mounted on a lever 6 pivoted as at 7 and carrying a float 8 at the end opposite to the loosely hanging valve 5. It will thus be seen that as the level of fuel in the housing 1 rises, the valve 5 is moved toward closing position. Similarly, a drop in the fuel level tends to move the valve 5 toward the open position. Downwardly depending from the cover 2 is a standpipe or bell 9, the lower edge of which normally extends below the fuel level. Extending upwardly into the interior of the bell 9 through its open bottom is a duct 10 downwardly connected with a liquid fuel line 11 which extends to the burner unit A. The pipe 10 has at its upper end a metering aperture 12. Extending into the metering aperture is a limiting or adjusting valve 13 which is manually adjustable on the threaded rod 14, the lower end of which rotatably engages a bracket 15 to which is secured a float 16. The level of the valve 13 in relation to the float 16 may be varied by rotating the threaded stem 14, the top of which is shown as accessible through an aperture 17 in the cover 2.

The level of the metering valve 13, and therefore its relation to the metering orifice 12 through which fuel flows to the burner, responds not only to the level of the float 16, but to the thrust of the pin 18. This pin is normally biased toward upward movement by the spring 19 which is compressed between an abutment 20 on the pin and an abutment or wall 21 within the bell 9. The upper end of the pin extends upwardly through an open-topped bore in a sleeve 22 which extends upwardly from the cover 2. The spring 19 is normally effective to elevate the pin 18 to a position in which its upper end extends upwardly above the top of the sleeve 22. Mounted on an abutment 23 on the top of the cover 2 is a time delay device including a bi-metal or warping bar 24 which carries preferably a suitable heat storage element 25. It also carries a resistance 26, the circuit and operation of which will later be described. It will be understood that when the warping bar 24 is cold, it takes the position in which it is shown in Fig. 1. When it is heated, it warps upwardly, permitting the spring 19 to elevate the pin 18. This withdraws the lower end of the pin 18 from contact with the metering valve 13 and leaves the metering aperture 12 to be controlled solely by the position of the float 16.

It will be noted that in the form herein shown, the warping bar 24 carries a hook or abutment

24a which, when the warping bar is cold, is effective to flex the switch blade 27 to the inoperative position shown in Fig. 1. The blade is mounted on an insulating structure 28 which also carries the leaves 29 and 30 with their respective contacts 29a and 30a. Thus, when the warping bar 24 rises it will close circuits through 29a and 30a which circuits are broken when the warping bar again returns to the position in which it is shown in Fig. 1.

The type of burner herein shown is of the so-called pot or vaporizing type and includes the burner pot 40, with a plurality of primary air inlets 41 spaced circumferentially thereabout and located at various levels. Secondary air to complete the combustion of the mixture formed by the primary air and vaporized fuel may be supplied, for example, by the secondary air inlets 42. 43 is any suitable flame ring and 44 indicates the wall of any suitable combustion chamber or radiator located above the flame ring 43. 45 indicates a pilot ring located above the lowest row of primary air inlets 41. It will be understood that liquid fuel for combustion is supplied along the duct 44 to the control and ignition unit 46. 47 indicates any suitable opening to the interior of the burner pot 40. In the normal use of the device, the liquid fuel supplied through the inlet 47 flows across the bottom of the pot 40 and is vaporized by the heat of combustion taking place in or above the pot. The vaporized fuel rises and, at the high-fire stage, receives sufficient primary air through the inlets 41 to produce a rich mixture. As this mixture rises upwardly to and past the level of the secondary air inlets 42, it receives adequate secondary air to produce a combustible mixture which burns at or above the top of the flame ring 43. At low fire, as the rate of fuel delivery is reduced to a minimum, the level of combustion drops until combustion takes place at or just above the pilot ring 45. At that stage, the lowest row of primary air inlets 41 provides adequate primary air and as the primary mixture flows upwardly through and above the pilot ring 45, it receives its secondary air from the air delivered into the pot by the intermediate and upper apertures 41.

It will be understood that in the structure herein shown air is supplied under pressure. 60 indicates a closed chamber which surrounds the pot 40. 61 is a fan housing with any suitable air inlet means not shown. 62 diagrammatically indicates a fan and 63 a fan motor. It will be understood that when the motor circuit is closed the motor 63 drives the fan 62 and delivers air under pressure to the interior of the housing 60 and thus to and through the apertures 41 and 42. At the same time, the increased air pressure within the housing 60 is communicated through an air duct 64 to the closed interior of the float chamber 1. Since the lower edge of the stand-pipe or bell 9 is at all times below the liquid fuel level, the increase in air pressure within the chamber 1 tends to reduce the oil level and thus move the float 8 toward the valve opening position. There is a varied supply of liquid fuel along the duct 3. The liquid fuel level within the bell 9 is at an adequate level to flow through the metering aperture 12 and thus to flow to the burner pipe.

70 generally indicates a hot wire ignition coil which is shown as having any suitable wick 71 whereby liquid fuel is picked up from the bottom of the fitting 46 for easy ignition by the coil 70 when current is passing through it. 72 is a warp-

ing bar or heat motor which, when cold, takes the vertical position in which it is shown in Fig. 1. When the pot 40 is hot, the warping bar 72 warps to the dotted line position of Fig. 1. It is connected by any suitable connector 73 with the spring 74 which carries a closure 75 to close an air inlet 76 in an upper part of the ignition unit 46. The inlet 76 is effective to supply air for combustion of the liquid fuel on the wick 71 when it is vaporized and ignited by the hot wire ignition coil 70. It will also be seen from Fig. 1 that when the heat motor 72 warps to the right, referring to the position of the parts in which they are shown in Fig. 1, it permits the spring contact 77 to snap from the full line or circuit closing position to the dotted line or circuit breaking position.

Referring to the wiring diagram, 80, 81 indicate any suitable connections to a source of electric current. 82 is a transformer for the ignition coil 70. 83 is a resistance in a motor circuit for low-speed motor operation. 84 is an electrical translating device in the form of a relay coil adapted to operate the below described switch structure generally indicated at 85. 86 is a transformer which powers the relay coil 84 and also powers an anticipator coil 87 associated with a room thermostat 88. 89 is a normally fixed contact opposed by any suitable movable contact of the room thermostat 88.

In the operation of the device, a primary electric circuit is normally closed from the main power lines 80 and 81, through the primary side of the transformer 82, the normally closed switch contacts 100 and 100b, and the contacts 77-77a of a switch means associated with the burner 40 which contacts are closed when the burner is cold. Assuming that the burner is initiating its operation, and that the room thermostat 88 is calling for heat, a secondary circuit is closed through the contact 89 and the secondary winding of the transformer 82. Thus, the relay coil 84 is energized and moves the switches 100, 101 and 102 into circuit closing relation with the contacts 100a, 101a and 102a. It will be observed that the switches 100, 101, and 102 are spring-biased upwardly (spring not shown) so that when the relay coil 84 is not energized said switches occupy the positions shown in Fig. 2. The closure of the switch 102 energizes a first motor circuit including the motor 63, and the blower 61 then begins to supply air to the interior of the housing 60 and through the duct 64 to the interior of the housing 1. The closing of the switch 101 closes a circuit through the cold contacts 77-77a of the switch means at the burner and through the primary winding of the transformer 82, the secondary of which in turn energizes the circuit which includes the hot wire ignition coil 70. The closure of the switch 100 closes a holding circuit which maintains energization of the transformer 82 so that it is continually energized. The relay 84 is of the usual slow-acting type and has a residual magnetism 65 metallic portion on it, so that sufficient residual magnetism will remain in the metallic mass after the spring switch arm 100 has disengaged from the contact 101b. The armature of the relay carries an inertia element 84' to insure the proper switchover from contact 101b to contact 100a. Initially, the switch 77 maintains the position in which it is shown in Fig. 2, which is the position it keeps when the pot 40 is cold. The effect of the delivery of pressure to the pipe 64 to the interior of the housing 1 is to raise the

level of liquid fuel within the standpipe or bell 9. As a result, fuel flows through the orifice 12 and the duct 14 to the passage 46 and, past the ignitor coil 70, to the bottom of the pot 40. Meanwhile, air is free to flow into the fitting 46 through the open inlet 76.

During the initial delivery of fuel, current is also supplied by the transformer 36 through the secondary electric circuit to the resistance 26 as long as the room thermostat 88 is in closed relation with the switch 89. The result is to heat the warping bar 24 and to store heat in the heat storage element 25. The result is a slow up-warping of the warping bar 24 which eventually releases the switch spring 27 to permit circuits to be closed through the contacts 29a and 30a. However, since the hook 24a is not actually secured to the spring 27, the up-warping of the bar 24 continues for a time after the circuits through 29a and 30a are closed. The result is a lifting of the pin 18 by the spring 19 which permits the valve element 13 to be lifted by the float 16. Meanwhile, the pot 40 is heating up and it eventually warps the heat motor 72 which releases the switch 77 from the full line to the dotted line position of Fig. 1. In other words, it leaves a contact 77a and moves into circuit closing relation with a contact 77b. One result is to close the air inlet 76 by means of the movable closure 75. Another result is that the circuit through the primary of the ignition transformer 82 is opened to de-energize the igniter 70. Another result is to complete an auxiliary circuit through 30a which cuts in the resistance 83 to complete a second motor circuit designed for low-speed operation of the motor 63 when the first motor circuit is broken at 102, 102a. However, as long as current continues to flow uninterruptedly through switch 102 to the motor 63 during the so-called high fire, resistance 83 will have no effect as it is only placed in the power line to the motor 63 when switch 102 has become disconnected by the de-energization of coil 84 which is under control of the thermostat 88. As heat is delivered from the pot 40 and from the burner unit 44 to the space in which the thermostat 88 is located the thermostat 88 warps back to the position in which it is shown in Fig. 2. This de-energizes the relay 84 returning switches 100, 101, 102 to their original position. It also de-energizes the resistance 26. However, the member 25 constitutes a heat storage element which, if desired, may be insulated. The result is that even though the heat is no longer called for, the downward movement of the warping bar 24 and thus the closure of the valve 13, is relatively gradual. When the thermostat circuit is broken, the metal mass or heat storage element 25 may retain sufficient heat so that a considerable time, say 5 to 10 minutes, is required to break the circuits controlled by the warping bar 24 through the hook 24a. As long as a circuit is made, the burner will continue to operate on high flame when the thermostat is calling for heat and at low flame when the thermostat circuit is broken.

The burner is turned on and ignited when the thermostat 88 calls for heat. Immediately the accelerator coil 87 starts to heat the thermostat which is possibly a 3 to 5 minute operation. At the same time the warping bar 24 responds to heat from the resistance 26 and starts to close the contacts 29a and 30a, possibly a 1 minute operation. And at the same time, due to the closure

of switch 101, the ignition coil 70 is energized and the burner is ignited, with the result that the heat motor 72 starts to heat, possibly a two or three minute operation.

5 When the contacts of the thermostat 88 break, the relay 84 is de-energized and current for the combustion air fan motor 63 must then go through the second motor circuit including the fan motor resistor 83, due to the opening of switch 102. 10 Normally, the burner will continue to operate at reduced fire until the thermostat 88 again calls for heat. Then the relay circuit including thermostat 88 is closed and high flame will again be produced.

15 Overrun is provided for the low fire; the burner will always be reduced from high fire to low fire and have several minutes on the low stage before shutting down completely. After such a shut-down, it is necessary to wait until the heat motor 72 is cold again before the burner can be restarted.

20 The needle or metering valve 13 is supported on the adjusting screw 14, carried by the float 16 so that as the float rises or falls, the effective opening through aperture 12 controlled by the needle valve 13 varies. If heavy oil is the medium in which float 16 floats, 16 will float high in the oil and needle valve 13 will be raised. On the other hand, if lighter fuel, for instance 25 gasoline, is in the float chamber, float 16 will sink further and needle valve 13 will reduce the size of the aperture but because the heavy oil is more viscous, the increased effective opening resultant from its weight will compensate for the increased 30 viscosity of the oil. On the other hand, with gasoline for instance the decreased viscosity permits gasoline to enter through a smaller aperture so the arrangement of float with its supported needle valve automatically compensates for 35 changes in fuel density and viscosity.

40 It will be realized that whereas I have described and shown a practical and operative device and mode of operation, nevertheless, many changes may be made in size, shape, number and disposition of parts without departing from the spirit of my invention. I, therefore, wish my description and drawings to be taken as in a broad sense illustrative or diagrammatic rather than as limiting me to my specific showing herein.

45 50 I claim:

55 1. In a device for generating heat, a liquid fuel burner of the vaporizing type, a housing in communication with the interior of the burner, a blower, a motor for driving the blower, a connection between the blower and the housing whereby the blower will increase the air pressure in the housing and the burner to above atmospheric pressure, a float chamber, an air duct extending from the housing to the float chamber so that the air pressure in the housing will be communicated to the float chamber, a liquid fuel supply line extending to the float chamber, a fuel delivery line extending from the float chamber to the burner, a valve mechanism adapted to control the flow of fuel from the supply line to the float chamber and maintain therein a predetermined fuel level, valve means for controlling the flow of fuel from the float chamber to the burner, an igniter interposed in the delivery line between the float chamber and the burner, a primary electric circuit, a secondary electric circuit including switch means responsive to changes in ambient temperature and which switch means is closed and opened at predetermined temperatures, means whereby said secondary electric cir-

cuit is operatively associated with said primary electric circuit to be energized thereby, electric translating means in said secondary electric circuit, a first motor circuit including switch means closed in response to the energization of the electric translating means in said secondary electric circuit, a circuit for said igniter including switch means closed in response to energization of said electric translating means in said secondary electric circuit so that the igniter is energized when said secondary electric circuit closes in response to predetermined changes in ambient temperature, a second motor circuit, a time delay device including a warping bar and switch means operated thereby controlling energization of the second motor circuit, means operatively connecting the warping bar with the valve means for controlling flow of fuel to the burner, means responsive to energization of the secondary electric circuit for operating the warping bar structure, said second motor circuit including means effective when said motor is being driven in response to energization by said second motor circuit to operate the blower at a slower rate of speed then when the motor is being driven in response to energization by the first motor circuit, both of said motor circuits being closed concurrently after the switch means in the second motor circuit has been actuated by movement of the warping bar, the blower during the period in which both the first and second motor circuits are closed being driven at a speed determined by the electrical characteristics of the first motor circuit, said igniter circuit and said primary circuit including switch means responsive to temperature adjacent the burner and operatively associated therewith so as to close said circuits through said switch means when the burner is cold and to open said circuits through said switch means when the burner has reached a predetermined temperature, and a holding circuit for said primary electric circuit including switch means responsive to energization of said electric translating means in said secondary electric circuit for connecting said holding circuit around the switch means which is responsive to burner temperature, so that, when the burner reaches a predetermined temperature, the ignition circuit is opened while the primary energizing circuit remains intact.

2. The device for generating heat described in claim 1 wherein an auxiliary circuit is provided to maintain the second motor circuit intact for a predetermined length of time after the first motor circuit has been de-energized following the opening of the switch means in the secondary electric circuit in response to a predetermined ambient temperature, said auxiliary circuit being operatively connected between the switch means of the time delay device and the switch means responsive to temperature at the burner and closed in response to a predetermined elevated temperature at the burner.

3. The device for generating heat described in claim 2 wherein the switch means associated with the time delay device includes a switch device in the auxiliary circuit arranged so that the auxiliary circuit will be de-energized in response to movement of the warping bar in cooling.

4. The device for generating heat as described in claim 1 wherein said switch means in the primary circuit responsive to temperature at the burner includes a heat motor adjacent the burner for operating said switch means.

5. The device for generating heat described in claim 4 wherein an air inlet aperture is provided in the burner structure adjacent to the igniter, 75

closure means for said aperture, and means operatively connecting the heat motor and said closure to open the aperture when the igniter is energized and the burner is cold and to close said aperture when the igniter is de-energized and the burner has reached a predetermined temperature.

6. The device for generating heat described in claim 1 wherein the warping bar of the time delay device is operatively associated with the valve means for controlling the flow of fuel from the float chamber to the burner and with the switch means of the time delay device so that, upon energization of the warping bar in response to a predetermined ambient temperature closing the secondary electric circuit, the warping bar will first initiate the admission of fuel from the float chamber to the fuel delivery line and will secondly energize the second motor circuit.

7. In a device for generating heat, a liquid fuel burner of the vaporizing type, a housing in communication with the interior of the burner, a blower housing connected to the first-mentioned housing, a blower whereby the air pressure in the first-mentioned housing and burner may be increased above atmospheric, a float chamber having a normal fuel level, an air duct connecting the interior of the first-mentioned housing with the interior of the float chamber, a liquid fuel supply line extending to the float chamber, admission valve mechanism adapted to control the flow of fuel through the supply line to maintain a predetermined normal fuel level in the chamber, a fuel delivery duct extending from the float chamber to the burner, valve means for controlling the amount of fuel admitted to the fuel delivery duct including a member defining an orifice in communication with the fuel delivery duct, valve mechanism responsive to changes in ambient temperatures for varying the effective size of the orifice, said orifice being positioned above the normal fuel level, means responsive to the air pressure in the first-mentioned housing for elevating the level of the fuel above the normal fuel level immediately adjacent said orifice for flow through said orifice, and a fuel density compensator for increasing the effective size of the orifice in response to an increase in the density of the fuel.

8. In a fuel control system for oil burners, a burner, means for supplying air at a pressure greater than atmospheric to the burner, a housing including a float chamber, means for supplying fuel to the float chamber, an inlet valve mechanism adapted to control the flow of fuel into the float chamber, said float chamber having means to maintain therein a normal predetermined fuel level, a fuel outlet, an outlet valve mechanism therefor adapted to vary the amount of fuel delivered through the outlet in direct proportion to the pressure of the air supplied to the burner and in accordance with predetermined ambient temperatures, said outlet valve mechanism including an outlet orifice positioned slightly above the normal fuel level in said float chamber, a float in the chamber, and means controlled by said float to increase the effective size of the orifice in response to an increase in fuel density resulting from the difference in densities involved in the use of more than one fuel, and means responsive to the pressure of the air supplied to the burner for elevating the level of the fuel above the normal fuel level immediately adjacent the orifice for flow therethrough.

9. In a fuel control system for oil burners, a

burner, means for supplying air at a pressure greater than atmospheric to the burner, a housing including a float chamber, means for supplying fuel to the float chamber, an inlet valve mechanism adapted to control the flow of fuel into the float chamber and to maintain within said float chamber a normal predetermined fuel level, a fuel outlet, an outlet valve mechanism therefor adapted to vary the amount of fuel delivered through the outlet in direct proportion to the pressure of the air supplied to the burner and in accordance with predetermined ambient temperatures, including means defining an orifice positioned slightly above the normal fuel level, means including a float in the chamber adapted to increase the effective size of the orifice in response to an increase in fuel density resulting from the difference in densities involved in the use of more than one fuel, and means responsive to the pressure of the air supplied to the burner for elevating the level of the fuel above said normal fuel level immediately adjacent said orifice for flow therethrough, said last-mentioned means including a depending cylinder on the inside of the float chamber encompassing said orifice and extending below the surface of the fuel at normal fuel level.

10. In a fuel control system for oil burners, a burner, means for supplying air at a pressure greater than atmospheric to the burner, a housing including a float chamber, means for supplying fuel to the float chamber, an inlet valve mechanism adapted to control the flow of fuel into the float chamber and to maintain within said float chamber a normal predetermined fuel level, a fuel outlet, an outlet valve mechanism therefor adapted to vary the amount of fuel delivered through the outlet in direct proportion to the pressure of the air supplied to the burner and in accordance with predetermined ambient temperatures, including means defining an orifice positioned slightly above the normal fuel level, a float in the chamber, means operable in response to movement of said float to increase the effective size of the orifice in response to an increase in fuel density resulting from the differences in densities involved in the use of more than one fuel, and means responsive to the pressure of the air supplied to the burner for elevating the level of the fuel above said normal fuel level immediately adjacent said orifice for flow therethrough, said outlet valve mechanism including a tapered element movable into and out of said orifice to vary the effective size thereof, said element being biased to move in a direction to increase the effective size of the orifice by the float in response to an increase in fuel density, and means for resisting movement of said tapered element under the influence of said float bias, said last-mentioned means including means for rendering said resistance means ineffective to resist the float bias in response to a predetermined ambient temperature.

11. In a fuel control system for oil burners, a burner, means for supplying air at a pressure greater than atmospheric to the burner, a housing including a float chamber, means for supplying fuel to the float chamber, an inlet valve mechanism adapted to control the flow of fuel into the float chamber and to maintain within said float chamber a normal predetermined fuel level, a fuel outlet, an outlet valve mechanism therefor adapted to vary the amount of fuel delivered through the outlet in direct proportion to the pressure of the air supplied to the burner and in accordance with predetermined ambient

temperatures, said outlet valve mechanism including an orifice positioned slightly above the normal fuel level, a float in the chamber, means operable in response to movements of said float to increase the effective size of the orifice in response to an increase in fuel density resulting from the differences in densities involved in the use of more than one fuel, and means responsive to the pressure of the air supplied to the burner for elevating the level of the fuel above said normal fuel level immediately adjacent said orifice for flow therethrough, said outlet valve mechanism including a tapered element movable into and out of said orifice to vary the effective size thereof, said element being biased by the float to move in a direction to increase the effective size of said orifice in response to an increase in fuel density, means for resisting said movement of said element, said last-mentioned means including means for rendering said resisting means ineffective to resist said float bias in response to a predetermined ambient temperature, and yielding means biasing the tapered element in the same direction as said float.

12. In a fuel control system for oil burners, a burner, means for supplying air at a pressure greater than atmospheric to the burner, a housing including a float chamber, means for supplying fuel to the float chamber, an inlet valve mechanism adapted to control the flow of fuel into the float chamber and to maintain within said float chamber a normal predetermined fuel level, a fuel outlet, an outlet valve mechanism therefor adapted to vary the amount of fuel delivered through the outlet in direct proportion to the pressure of the air supplied to the burner and in accordance with predetermined ambient temperatures, said outlet valve mechanism including an orifice positioned slightly above the normal fuel level, a float in the chamber, means operable in response to movement of said float to increase the effective size of the orifice in response to an increase in fuel density resulting from the differences in densities involved in the use of more than one fuel, means responsive to the pressure of the air supplied to the burner for elevating the level of the fuel above said normal fuel level immediately adjacent said orifice for flow therethrough, said outlet valve mechanism including a tapered element movable into and out of said orifice to vary the effective size thereof, said element being biased for movement in a direction to increase the effective size of said orifice by the float in response to an increase in fuel density, means resisting said movement of said element, said last-mentioned means including means for rendering said resisting means ineffective to resist said float bias in response to a predetermined ambient temperature, and manually operable means for adjusting the position of the tapered element with respect to the orifice for any predetermined position of the float.
